DESIGN FOR CHESSMEN

Harold Vernon Chase, Evanston, Ill.

Application February 5, 1940, Serial No. 90,058

Term of patent 14 years

To all whom it may concern:

Be it known that I, Harold Vernon Chase, a citizen of the United States, residing in Evanston, in the county of Cook and State of Illinois, have invented a new, original, and ornamental Design for Chessmen, of which the following is a specification, reference being had to the accompanying drawing, forming a part thereof.

In the drawing Figures 1, 2, 3, 4, 5 and 6 are perspective views of the chessmen showing my new design.

I claim:

The ornamental design for chessmen, substantially as shown.

HAROLD VERNON CHASE.
